ABSTRACT OF THE DISCLOSURE

A plural section electron multiplier device having separate-strip portions for providing improved gain and resolution. The purpose of the foregoing abstract is to enable the Patent Office and the public generally and especially the scientist, engineer, or practitioner in the art who is not familiar with patent or legal terms or phraseology to determine quickly from a cursory inspection the nature and essence of the technical disclosure of the application. The abstract is neither intended to define the invention of the application, which of course is measured by the claims nor is it intended to be limiting as to the scope of the invention in any way.

This application is a continuation of application, Ser. No. 312,414, filed Sept. 30, 1963.

This invention relates to channel electron multipliers and more particularly to channel electron multipliers disposed in series relationship for amplifying a radiation image.

In copending patent application U.S. Ser. No. 23,574, filed Apr. 20, 1960, by George W. Goodrich and W. C. Wiley, there is fully disclosed a tube type channel electron multiplier. In this type multiplier, the inside surface of the tube is resistive and has secondary emissive properties. Upon the application of a voltage difference between the ends of the tube, current flows through the inner resistive surface producing an electric field in an axial direction through the region defined by the tube. Electrons or particles of suitable energy entering the input end of the tube are multiplied through secondary emission before they emerge from the output end of the tube.

In multipliers of this type, the output current is limited by the magnitude of current through the resistive inner surface referred to as "strip current," since it is this current which supplies the electrons in the secondary emission process. However, the strip current cannot be increased without limit to obtain greater output currents because at some point the amount of heat generated in the strip will exceed the equilibrium heat dissipation characteristics of the multiplier and thermal runaway will occur, eventually destroying the multiplier. Thus, the output current of a channel electron multiplier is governed by the magnitude of available strip current, subject to a limitation imposed by its thermal dissipation characteristics.

One method of surmounting the relatively low output current capabilities of a single channel multiplier is simply to increase the surface area of the tube with a corresponding decrease of inner surface resistance. In this way, a larger strip current can be carried; a greater amount of heat can be dissipated through the increased channel surface area, and a higher output current will be achieved. However, in certain applications, for example star tracking devices, where a single channel having an input diameter of 0.020 inch or smaller is dictated by optical resolution requirements, the relatively low output current of the channel limits the effectiveness of the tracking device.

That is, a single channel having a length to diameter ratio of 60:1 and an input diameter of 0.020 inch typically produces a stable maximum output current of only 0.2 microampere.

5 In accordance with this invention, higher output currents are obtained by disposing continuous channel electron multipliers in series relationship to overcome the disadvantageous low output current limitation of a single channel of required resolution capability. A first channel having required resolution capability has disposed at its output a second channel having a larger diameter and greater strip current carrying capacity than the first. In this way, an advantage is achieved whereby the output current of the two channels is substantially higher than 15 the output current of a single channel multiplier of the same resolution capability as the first channel.

For example, a 0.020 inch first channel of 30:1 length to diameter ratio, and a 0.30 inch second channel of 30:1 length to diameter ratio are capable of producing an output current of 2.0 microampères, an improvement of a decade over a single 0.020 inch channel multiplier of 60:1 length to diameter ratio. Of course, in the example given, the total length of the two channels is 1.500 inches whereas the total length of the single channel is only 25 1.200 inches. This disadvantage, however, is easily surmounted by the substantially greater output current obtained from the first and second channels.

An object of this invention is to provide channel electron multipliers arranged in series for the amplification 30 of radiation images.

Another object of this invention is to provide a first channel resolution element position to direct its output current into a second channel of larger diameter.

Other objects and advantages will become apparent 35 from the following detailed description and from the appended drawings and claims.

In the drawings:

FIGURE 1 is a perspective view, partly broken away illustrating an embodiment of this invention.

40 FIGURE 2 is a schematic diagram illustrating the embodiment in FIGURE 1 and showing the associated electrical circuitry and resultant electron paths.

In FIGURE 1, a channel electron multiplier 2 is positioned to receive particles, such as ions or electrons, from a source (not shown). For example, the channel 2 may receive electrons from a photocathode. Positioned at the output of the channel 2 is another channel electron multiplier 4 of larger diameter. Thus, the output current of channel 2 provides the input current for channel 4. This input current is subsequently multiplied and collected by the anode 6 which is disposed relative to the output end of channel 4 to collect electrons passing through the channel.

55 Direct voltages of suitable magnitude are applied to the elements disclosed above from a direct voltage source 8. For example, as shown in FIGURE 2, direct voltages of -2000 volts, -1150 volts, -1150 volts, -300 volts, and 0 volt may be applied respectively, to the input 10 and output 12 of channel 2, the input 14 and output 16 of channel 4 and the anode 6.

60 When electrons are introduced to the input end of the multiplier 2, they successively strike the surface of the channel 2 as shown by the path 18 in FIGURE 2 and are multiplied through secondary emission. This multiplied output current from channel 2 then serves as the input current to channel 4 which is also multiplied through secondary emission being collected by the anode 6.

65 It should be understood that the channels 2 and 4 and the anode 6, operate in a vacuum environment.

70 Although only two channels (2 and 4) have been used in describing this invention, it will be recognized that

supplementary channels can be added to provide even greater output currents.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

What is claimed is:

1. An electron multiplier device for amplifying a radiation image excitation signal and having an improved output current for a selected resolution capability comprising a first elongated electron multiplier portion of a cross-sectional dimension to establish a selected resolution capability for the radiation image and receiving and amplifying a radiation-image excitation signal, and a second electron multiplier portion having a greater cross-sectional dimension than at least a portion of said first electron multiplier portion and disposed to amplify a signal from said first electron multiplier portion, each of said electron multiplier portions having a secondary electron emissive surface and a longitudinal resistance, means including a pair of leads from a voltage source connected to spaced portions of said first portion for establishing a voltage across the resistance of said first portion for establishing a strip current through said resistance, and means including another pair of leads from a voltage source connected to spaced portions of said second portion for establishing a voltage across the resistance of said second portion for establishing a strip current through said resistance.

2. The combination of claim 1 in which said second portion has a higher strip current carrying capability than said first portion and in which strip current in said second portion is greater than the strip current through said first portion.

3. The combination of claim 1 in which each of said first and second portions amplifies said signals in a series of successive stages.

4. The combination of claim 3 in which each of said first and second portions is cylindrical.

5. The combination of claim 4 in which each of said first and second portions has a circular cross section.

6. An electron multiplier device for amplifying a radiation image excitation signal and having an improved output current for a selected resolution capability comprising a first elongated electron multiplier portion of a cross-sectional dimension to establish a selected resolution capability for the radiation image and receiving and amplifying a radiation-image excitation signal, and a second electron multiplier portion having a greater cross-sectional dimension than any portion of said first electron multiplier portion and disposed to amplify a signal from said first electron multiplier portion, each of said electron multiplier portions having a secondary electron emissive surface and a longitudinal resistance, means including a pair of leads from a voltage source connected to spaced portions of said first portion for establishing a voltage across the resistance of said first portion for establishing a strip current through said resistance, and means including another pair of leads from a voltage source connected to spaced portions of said second portion for establishing a voltage across the resistance of said second portion for establishing a strip current through said resistance.

7. An electron multiplier device for amplifying a radiation image excitation signal and having an improved output current for a selected resolution capability comprising a first elongated electron multiplier portion of a cross-sectional dimension to establish a selected resolution capability for the radiation image and receiving and amplifying a radiation-image excitation signal, and a second electron multiplier portion having a greater cross-sectional dimension than at least a portion of said first electron multiplier portion and disposed to amplify a signal from said first electron multiplier portion, each of said electron multiplier portions having a secondary elec-

tron emissive surface and a longitudinal resistance, means including a pair of leads from a voltage source connected to spaced portions of said first portion for establishing a voltage across the resistance of said first portion for establishing a strip current through said resistance, and means including another pair of leads from a voltage source connected to spaced portions of said second portion for establishing a voltage across the resistance of said second portion for establishing a strip current through said resistance for supplying electrons emitted by said second portion in the secondary emission process effectively independently of any supply thereof via the strip current in said first portion.

8. An electron multiplier device for amplifying a radiation image excitation signal and having an improved output current for a given resolution capability comprising a first elongated electron multiplier portion of a cross-sectional dimension to establish a selected resolution capability for the radiation image and receiving and amplifying a radiation-image excitation signal in a series of successive stages, and a second electron multiplier portion disposed to amplify a signal from said first electron multiplier portion in a series of successive stages, each of said electron multiplier portions having a secondary electron emissive surface and a longitudinal resistance, means including a pair of leads from a voltage source connected to spaced portions of said first portion for establishing a voltage across the resistance of said first portion for establishing a strip current through said resistance, and means including another pair of leads from a voltage source connected to spaced portions of said second portion for establishing a voltage across the resistance of said second portion for establishing a strip current through said resistance, said second portion having a higher strip current carrying capability than said first portion, and said strip current through said resistance of said second portion being greater than the strip current through said resistance of said first portion.

9. An electron multiplier device for amplifying a radiation image excitation signal and having an improved output current for a given resolution capability comprising a first elongated electron multiplier portion of a cross-sectional dimension to establish a selected resolution capability for the radiation image and receiving and amplifying a radiation-image excitation signal in a series of successive stages, and a second electron multiplier portion disposed to amplify a signal from said first electron multiplier portion in a series of successive stages, each of said electron multiplier portions having a secondary electron emissive surface and a longitudinal resistance, means including a pair of leads from a voltage source connected to spaced portions of said first portion for establishing a voltage across the resistance of said first portion for establishing a strip current through said resistance, and means including another pair of leads from a voltage source connected to spaced portions of said second portion for establishing a voltage across the resistance of said second portion for establishing a strip current through said resistance for supplying electrons emitted by said second portion in the secondary emission process effectively independently of any supply thereof via the strip current in said first portion, said second portion having a higher strip current carrying capability than said first portion, and said strip current through said resistance of said second portion being greater than the strip current through said resistance of said first portion.

10. An electron multiplier portion device comprising a plurality of electron multiplier portions disposed in serial relationship, a first electron multiplier portion in the plurality being disposed to receive an excitation signal, each of the electron multiplier portions in said plurality having a secondary electron emissive resistive surface, means for connecting leads from a voltage source to two spaced areas on each of the portions for producing along each thereof a strip current, each multiplier portion

of the plurality having a higher strip current carrying capability than each preceding multiplier portion and being disposed to amplify the output of the preceding multiplier portion, the current between leads of a succeeding portion being higher than the current between leads of a preceding portion.

11. An electron multiplier portion device comprising a plurality of electron multiplier portions disposed in serial relationship, a first electron multiplier portion in the plurality being disposed to receive an excitation signal, each of the electron multiplier portions in said plurality having a secondary electron emissive resistive surface, means for connecting leads from a voltage source to two spaced areas on each of the portions for producing along each thereof a strip current, each multiplier portion of the plurality having a greater cross-sectional dimension and a higher strip current carrying capability than each preceding multiplier portion and being disposed to amplify the output of the preceding multiplier portion, the cur-

rent between leads of a succeeding portion being higher than the current between leads of a preceding portion.
